UNITED STATES PATENT OFFICE.

WALTER R. GREEN, OF CHICAGO, ILLINOIS.

DESIGN FOR A DROP-SIDE MUD-GUARD AND SPLASHER ATTACHMENT.

50,346.

Specification for Design.

Patented Feb. 20, 1917.

Application filed September 8, 1916. Serial No. 119,118. Term of patent 14 years.

To all whom it may concern:

Be it known that I, WALTER R. GREEN, a citizen of the United States, and a resident of the city of Chicago, in the county of Cook and State of Illinois, have invented a new, original, and ornamental Design for a Drop-Side Mud-Guard and Splasher Attachment, of which the following is the specification, reference being had to the accompanying drawings, forming a part thereof.

In the drawings:

Figure 1 is a side elevation of a drop side

mud guard and splasher attachment, showing my new design.

Fig. 2 is an interior plan view thereof.

I claim:

The ornamental design of a drop side mud guard and splasher attachment, as shown.

WALTER R. GREEN.

Witnesses:

LAWRENCE REIBSTEIN,

EARL M. HARDINE.
